UNITED STATES PATENT OFFICE.

EUGENE DIX AIKEN, OF ROCHESTER, NEW YORK, ASSIGNOR TO THE CARBOX CORPORATION, OF ROCHESTER, NEW YORK.

CARBURIZING BOX.

Application filed January 14, 1924. Serial No. 686,018.

To all whom it may concern:

Be it known that I, EUGENE DIX AIKEN, a citizen of the United States, and a resident of Rochester, in the county of Monroe and State of New York, have invented a new and Improved Carburizing Box, of which the following is a specification.

The present invention relates to boxes employed in the cementation and carburizing of steel, an object of the invention being to provide a box of this character that will be practically gas-tight.

It is well known that when solid cements are used as the packing material with which the boxes are charged, and the boxes subjected to carburizing heat, certain carbonaceous gases are formed and that the transfer of carbon from the packing material is accomplished chiefly by these gases. Also, the greater the gas pressure within the boxes, up to the limit of approximately 50 lbs. per square inch, when the articles being treated have reached the transformation point or temperature at which cementation takes place, the faster penetration of carbon into the steel is obtained, that is, the time necessary to obtain a predetermined depth of case on the articles is lessened and better results obtained accordingly as the quantity and pressure of carburizing gases are increased.

The common practice heretofore has been to place a cover over the open face of a carburizing box and depend upon fire-clay, with which the cover is luted to the side walls of the box, to form an effective seal against the escape of gas. This method, however, is unsatisfactory for the reason that the moist clay dries and breaks off when subjected to the intense heat of the furnaces in which the boxes are placed and is insufficient to withstand the gas pressure generated within the boxes. Furthermore, air striking the heated carburizing material causes the exposed parts thereof to turn to ash.

As an experiment to determine when the carburizing gases begin to form and to what extent they escape before cementation takes place, I charged a box with carburizing material and sealed it absolutely gas-tight with the exception of a single vent to which a tube was connected leading from the furnace in which the box was placed. At about 850° F., gas pressure had formed sufficiently in the box so that the gas began to burn at the out-

let of the conductor pipe. At a temperature of 870° F., the flame at the pipe outlet was one and one-half inches long and gradually increased until it measured six inches when the temperature had reached 1210° F. Thereafter, as the temperature increased, the flame gradually shortened and became extinguished when the temperature reached 1658° F. The temperature at which transformation of the steel takes place and at which cementation commences being about 1540° F., it will readily be seen from the foregoing that the greatest quantity and pressure of gas is developed at a temperature considerably below the transformation point, and that with a leaky box practically all of the carburizing gas will have escaped without functioning in forming the case on the articles and, also, the solid cement will have lost considerable of its carbon content, thus reducing its effectiveness as a carburizing agent.

In the construction of a carburizing box that will be gas-tight or practically so, I do away with the necessity of and inconvenience of luting the cover on the box, this being another object of the invention, and a further object is to provide a cover that may be readily placed on and removed from the box and that will be held in position by simple but effectively operable clamping devices.

A further object of the invention is to provide a gasket or suitable packing medium of a dry material intermediate the box and a flanged cover, and so positioned relative to the two members that an effective sealing of the box is obtained even though there is a comparatively loose fitting of the cover.

A further object of the invention is to provide a box and cover with a packing medium interposed between them and to employ wedges insertable between one of the members and overhanging portions of the other member as means for drawing the cover and box together and against said packing medium, the wedges also functioning to hold the cover against warping.

A further object of the invention is to provide a box adaptable, if desired, to being placed in a furnace bottom side up.

A further object of the invention is to provide means interchangeable with the cover for holding the packing medium in place, in the event that sand or other such granular

substance is used, when the box is turned bottom side up to discharge the contents.

And, a still further object of the invention is to provide a box of the character described that will be inexpensive to manufacture, that will stand more usage than the ordinary box cast of like metal, and that can be sealed more quickly and effectively than one in which a luting material is used for attaching the cover.

To these and other ends the invention consists of certain parts and combinations of parts as will be fully set forth in the following description and particularly defined in the appended claims.

The accompanying drawings illustrating the invention are as follows:—

Figure 1 is a top plan view of a rectangular box with a portion of the cover broken away.

Fig. 2 shows the lower part of the box in end elevation and the upper part in section on the line 2—2, Fig. 1.

Fig. 3 is a sectional detail on the line 3—3, Fig. 1.

Fig. 4 is a perspective view of one of the wedge pieces.

Fig. 5 is a top plan view of a cylindrical box with parts of the cover broken away.

Fig. 6 is a sectional view of the upper part of the box taken on the line 6—6, Fig. 5.

Fig. 7 is a side view partly broken away of the cover for the box shown in Figs. 5 and 6.

Fig. 8 is a fragmentary side view of the cylindrical box with the cover removed.

Fig. 9 is a top plan view of another modification of the cylindrical box.

Fig. 10 shows in detail the member interchangeable with the cover for holding the packing medium in place when the box is tipped over to discharge the contents.

Fig. 11 is a sectional detail of the box showing such interchangeable member in position; and, Fig. 12 is a sectional detail on line 12—12, Fig. 9.

Similar reference numerals refer to similar parts throughout the several views.

Referring first to Figs. 1 to 4, inclusive:—
The box therein shown is rectangular with the numeral 1 representing the bottom, 2 the side walls and 3 the end walls, while a removable cover 4 formed with a downwardly projecting marginal flange 5 is provided for the open top side. The side and end walls 2 and 3 are increased in thickness at the open side of the box and formed therein is an upwardly opening channel or groove 6 for receiving a gasket or packing 7 of any suitable non-combustible material as sand or asbestos rope and the flange 5 of the cover 4, the channel being somewhat wider than the flange 5 so as to allow the cover being properly positioned even though there might be slight irregularities in alignment

of the mating parts, both the box and cover being rough castings and neither having any finished surfaces.

Formed on the side walls 2 of the box are upstanding lugs 8 provided with reinforcing ribs and having inwardly turned lateral projections 9 the under faces 10 of which are preferably slightly inclined in the direction of the length of the box, these projecting portions 9 overhanging the cover 4 so that wedge pieces 11 may be inserted between the cover and projecting box members, in the manner clearly indicated in Figs. 1, 2 and 3, for the purpose of clamping the cover firmly on the box and against the packing medium in the channel 6. This channel, it will be noticed, being substantially in line with the side and end walls of the box, the pressure due to the wedges being driven home will be exerted directly against these side and end walls. The wedges are preferably made of a metal having a greater expansion under heat than that of the box so that when the boxes are subjected to furnace heat the greater expansion of the wedges will tend to draw the cover and box still more firmly together.

The side walls 2 of the box are provided with longitudinally extending ribs 12 whereby the box may be readily picked up by a fork or other suitable handling implement, and lugs or pads 13 are formed on the bottom wall so that a space will be provided between the box bottom and the supporting surface. The box may be placed in a furnace with either the top or bottom uppermost, and in the latter event the projecting portions 9 on the lugs 8 will act as supporting feet.

In Figs. 5 to 8, inclusive, there is shown a cylindrical box 14 having an annular groove 15 for receiving a packing 7 and the annular rim or flange 16 of a circular cover 17. In this instance wedges 11 are also used to hold the cover in place, such wedges engaging the cover and the inclined under faces of the laterally turned overhanging portions 18 of two oppositely arranged lugs 19 upstanding from the side wall of the box, the inner faces of these lugs being tangential to the cover so that the latter may be placed on the box by inserting it under the overhanging lug portions 18.

In the cylindrical box shown in Fig. 9 there are three regularly spaced lug members 20, 20 and 21, each provided with an inwardly turned lateral projection under which a wedge 11 engages for tightening the cover 22. In this construction of box the lug 21 is removable to permit placing and removing the cover, and to this end any suitable means for detachably holding the lug in place or pivotally mounting it may be employed. A preferred way to removably secure the lug is to have it engage between

two spaced ears 23 projecting outwardly from the side of the box and to hold it against upward movement by forming abutments 24 on its inner end for engaging under 5 the said ears.

This illustration shows the box as having a tubular core 25 and the cover as having an opening 26 aligned with the core. Also, the box has two annular grooves or channels 27 and 28, the channel 27 being in the outer wall and the channel 28 in the wall of the tubular core, while co-operating flanges 29 and 30 for the channels 27 and 28, respectively, depend from the cover 22.

15 When using the boxes, the articles 33 to be case hardened are placed therein and embedded in a suitable cement or carburizing material 34, after which the covers are placed in position under the overhanging 20 box projections and the wedges driven into place so as to firmly compress the gasket or packing medium 7. In order to remove the covers, the wedges are driven out, the covers raised so that marginal flanges clear the top 25 edges of the boxes and then moved sidewise from under the overhanging projections.

In each instance the inner wall of the channel for receiving the sealing medium preferably projects above the outer wall so 30 that, in the event a granular substance such as sand is used the same may be brushed out of the channel with less danger of particles thereof falling into the box. Also, this construction permits a more ready alignment of the cover.

35 My invention also contemplates the provision of means for holding the sealing medium in place, should a granular substance be used, when the boxes are turned bottom side up to discharge the contents. To this end, according to the shape of the box, whether cylindrical or rectangular, a template is formed to fit within the channel and cover such substance. At 31, in Figs. 10 40 and 11, there is shown such a member adapted for use with a box such as illustrated in Figs. 1 and 2. This member is interchangeable with the cover and is held in place by wedges engaging under the overhanging projections which co-operate with 45 the wedges 11 in holding the cover in place. In fact the wedges 11 by placing them edge-wise may be used for this purpose, and to this end a side face thereof is also tapered.

50 From the foregoing it will be seen that I have provided a carburizing box employing a non-combustible and preferably dry packing or sealing medium between the box and cover and that such packing is so arranged as not to require replacing each time the box is used. Also, by the use of readily manipulated wedges co-operating with the cover and box so that the cover, which may 55 have a comparatively loose fit, is firmly held in place and the box made practically gas-

tight. Besides this the use of fire clay or other such luting material which has to be applied in a moist condition is eliminated and a box provided which by being practically gas-tight insures better results and a 70 considerable saving of time in the work done.

Although the box is primarily intended for carburizing, it may also be used for annealing purposes as the method of sealing 75 it will cause it to function equally well in keeping air out, as required when annealing, as preventing the escape of gas from within.

What I claim is:

1. In a device of the character described, 80 a box having a channel in the wall thereof at the open side of the box, a cover formed with a marginal flange adapted to be received in said channel, the sides of the cover terminating short of the outer wall of said channel, upstanding and inwardly turned projections cast integrally on opposite sides of said channel outer wall, and wedges engaging between the cover and said projections for holding the cover in place. 85

2. In a device of the character described, 90 a box having a channel in the wall thereof at the open side of the box, a noncombustible packing or sealing medium in said channel, a cover formed with a marginal flange which rests upon said packing and overhangs the inner wall of the channel, inwardly turned lateral projections on the wall of the box, and wedges engaging 95 between the cover and said projections for drawing the box and cover together and holding the cover in place. 100

3. In a device of the character described, 105 a box having a channel in the wall thereof at the open side of the box, a packing or sealing medium in said channel, a cover formed with a marginal flange which rests upon said packing and overhangs the inner wall of the channel, upstanding lugs on the wall of the box, inwardly turned lateral 110 projections on said lugs, and wedges engaging between the cover and said projections for drawing the box and cover together and holding the cover in place. 115

4. In a device of the character described, a box, a surrounding marginal portion of the wall of which at the open side of the box being increased in thickness and formed with an upwardly opening channel, a packing or sealing medium in said channel, a 120 cover formed with a marginal flange which rests upon said packing and overhangs the inner wall of said channel, upstanding lugs on the wall of the box, inwardly turned lateral projections on said lugs, and wedges engaging 125 between the cover and said projections for drawing the box and cover together and holding the cover in place.

5. In a device of the character described a 130 box, a surrounding marginal portion of the

- wall of which at the open side of the box being increased in thickness and formed with an upwardly opening channel, the inner wall of the channel projecting above the outer wall thereof, a packing or sealing medium in said channel, a cover formed with a marginal flange which rests upon said packing and overhangs the inner wall of the channel, upstanding lugs on the wall of the box, inwardly turned lateral projections on said lugs, and wedges engaging between the cover and said projections for drawing the box and cover together and holding the cover in place.
- 15 6. A carburizing box or the like having one side open, projections upstanding from the wall of the box, a cover, members carried by said projections extending over the cover, and wedging devices engaging between the cover and said members for drawing the box and cover together and holding the cover in place.
- 20 7. A carburizing box or the like having one side open, projections upstanding and turned inwardly from the wall of the box, a cover, and wedges engaging between the cover and the inturned portions of said projections for drawing the box and cover together and holding the cover in place, said projections comprising supporting feet when the box is turned bottom side up.
- 25 8. A carburizing box or the like adapted to be placed in a furnace with either its top or bottom uppermost, supporting members on the bottom of the box, upstanding projections on the wall of the box, a cover, and wedges engaging between said projections and the cover for drawing the box and cover together and holding the cover in place, said projections comprising supporting members when the box is placed bottom side up.
- 30 9. A carburizing box or the like adapted to be placed in a furnace with either its top or bottom uppermost, supporting members on the bottom of the box, upstanding and inwardly turned projections on the wall of the box, a cover, and wedges engaging be-
- tween the inturned portions of said projections and said cover for drawing the box and cover together and holding the cover in place, said projections comprising supporting members when the box is placed bottom side up. 50
10. In a device of the character described, a cylindrical box formed with a tubular core, the outer and inner walls of the box having annular channels therein at the open side of the box, a packing medium in said channels, a cover formed with outer and inner flanges adapted to rest upon said packing and be received in said channels, upstanding lugs on a wall of the box, lateral projections on said lugs, and wedges engaging between the cover and said projections for drawing the box and cover together and holding the cover in place. 55
11. In a device of the character described, a cylindrical box having an annular channel in the wall thereof at the open side of the box, a packing medium in said channel, a cover formed with a flange adapted to rest upon said packing and be received in said channel, a plurality of upstanding members on said wall, at least one of which is movable from an upstanding operative position, inwardly turned lateral projections on said members, and wedges engaging between the cover and said projections for drawing the box and cover together and holding the cover in place. 60
12. In a device of the character described, a box having a surrounding channel in the wall thereof at the open side of the box, a packing medium in said channel, a cover formed with a depending marginal flange which rests upon said packing and overhangs the inner wall of said channel, projections on the wall of the box overhanging the cover, wedges engaging between the cover and said projections for drawing the box and cover together and holding the cover in place, and a template formed to fit said channel and being interchangeable with said cover. 65
